LAWN MOWER BLADE SHARPENER

Frank D. Wulff, Chicago, Ill.

Application June 26, 1943, Serial No. 492,359

5 Claims. (Cl. 76—82.1)

This invention relates to unique improvements in a lawn mower blade sharpener.

One of the main objects of this invention is to provide an efficient and inexpensive device for sharpening the blades of lawn mowers and the like, which device is arranged to be held in the hand and to be conveniently drawn along the edge part of the blade for quickly sharpening the same.

Another object of this invention is to provide such a sharpening device which is sturdily built and is also economical in its construction, can be conveniently manipulated, and will render efficient service for an extended period of time.

A more particular object of this invention is to provide such a sharpening device which is provided with several abrading members, whereby to sharpen the edge as well as remove the burr from the blade, and wherein these members are arranged so as to be adjustable in order to place different parts of the members into active position and they are also readily removable and replaceable, whereby to greatly extend the period of efficient utility of this device.

These and various other objects and purposes and advantages are attained with this invention, as will become apparent from the following description, taken in connection with the accompanying drawing illustrating the invention in its preferred form, it being evident that other arrangements and forms of construction may be adopted in carrying out the objects and purposes of this invention.

In the drawing:

Fig. 1 is a view illustrating this invention in one of its forms of construction, showing the operative side thereof.

Fig. 2 is a longitudinal sectional view thereof, taken on line 2—2 of Fig. 1.

Fig. 3 is an end view thereof.

Fig. 4 is a cross-sectional view, taken on line 4—4 of Fig. 2, also showing a part of a blade in connection with the sharpener.

Fig. 5 is a perspective view of one of the abrading members.

Fig. 6 is a perspective view of the guide member which is effective in properly guiding the sharpener along the blade.

This sharpening device, in the form illustrated herein, comprises a main member or supporting member 11 whereon the several abrading members are mounted. This member 11 is substantially block-shaped and is arranged to be held in the hand; and it preferably includes a block 12 of hard wood which contains a flat operative side or face 13 whereon the abrading members 16

are mounted, and it has a hand-fitting part or handle 14 on the other side opposite said side 13. Said handle 14 is detachably mounted on the block, as by screws 15 or the like, to facilitate adjusting and mounting the various members of this device.

The abrading means or abrading members used in this illustrated device comprise a pair of abrading members 16 which are mounted spaced apart on said side 13, said members being arranged and adapted to abrade and act upon the narrowed edge part 17 of the blade 18 of a lawn mower and the like, as indicated in Fig. 4 of the drawing. Said abrading members further comprise a member 19, which is mounted between the two members 16 herein, and it projects from said side 13 and acts on the side of the blade adjoining the edge part 17, being effective in straightening said side and removing any burr that may be formed thereon.

These abrading members 16 and 19 herein are preferably provided in the form of flat files, substantially as indicated in the drawing, which are readily and inexpensively obtainable; and they are mounted on the operative side 13 of the block so as to allow for moving and adjusting and also for reversing the files, so as to place and to utilize different parts of each file on the device for sharpening action. The mounting means used herein therefore include adjustable holding elements or members, being shown herein as a pair of hook-bolts 21 for each file 16, each having a shank part extending thru the block 12 and being provided with a nut 22 for securing the bolt 21 and drawing the file firmly down onto the face 13 of the block. The member 19 is set partly into the block and extends partly outward from the face 13, as best shown in Fig. 4; and herein this block 12 is preferably made in two parts or halves, as illustrated, while one half may be provided with a slight groove for better receiving this file 19 therein. Screws or elements 23 are used to force these two parts of the block tightly together and to permit separation thereof when desired.

A guide member 24 is also provided herein, and it is preferably in the shape of a plate or strip of metal which has its intermediate part placed against the file 19 seated between the two halves of the block, and has a locking toe or flange 25 turned against the inward side of the block, to positively retain this member 24 in place. The outer part 26 of this plate is bent or slanted away from the file 19, so that the beveled or slanting edge part 17 of the blade 18 will fit properly be-

tween this guide member 24 and the adjoining file 19 in the sharpening operation.

In adjusting and reversing this file 19, the screws 15 are released and the handle 14 is removed from the block 12, also the screws 23 are loosened, to permit separation of the two halves of this block; and the file can then be removed and reversed, being thus enabled to be turned end-for-end and likewise edge-for-edge, so as to utilize at least four different portions of the file for sharpening action. The guide member 24 can then likewise be removed and renewed if necessary.

The files 16 can similarly be reversed, by releasing bolts 21, and they can furthermore be adjusted lengthwise toward either side of the block, as indicated by dot-and-dash lines at 21 in Fig. 1, so as to bring different parts of these files into use in the sharpening operation.

This blade sharpener can thus be readily and economically constructed, and is also convenient in operation for quickly and efficiently sharpening the blades of lawn mowers and the like.

I claim:

1. A lawn mower blade sharpener comprising a supporting member having a substantially flat side and a pair of files spaced apart on said side to act on the edge of the blade, a file mounted between said pair and projecting beyond them from said side to act on the side of the blade, means for mounting said files adjustably and replaceably on said member to bring different parts of said files into action, a guide plate projecting from said member adjacent said projecting file and cooperating therewith in guiding the sharpener along the blade, and means on said member for operating it by hand.

2. The subject matter set claim in claim 1, wherein the projecting file is a flat double-faced

file, and the supporting member is a block of two halves detachably secured together, holding said file and the guide plate therebetween, and said file is reversible end-for-end and edge-for-edge in said block.

3. The subject matter set forth in claim 1, wherein all the files are flat double-faced ones and they are reversible on the member.

4. A lawn mower blade sharpener comprising a block-shaped member carrying abrading means on one side thereof, means for mounting the abrading means on said side so as to have its longitudinal axis positioned transversely of the block and enable moving said means longitudinally for adjusting the same transversely of the block and place different parts of the abrading means into active position, a file extending longitudinally of the block and being mounted adjustably and reversibly to extend a short distance beyond said side and said abrading means, to act on the side of the blade, and guide means mounted adjacent said file and cooperating therewith for guiding the sharpener, said guide means being positioned to bear on the slanting edge part of the blade and urge the blade against said file during the sharpening operation.

5. A lawn mower blade sharpener comprising a supporting member having handle means on one side and a plurality of files mounted spaced apart on the opposite side adapted to act on the edge of the blade, a file positioned between said files and projecting beyond them to act on the side of the blade, means adjustably mounting said files to bring different parts thereof into active position, and guide means extending at a slant from said one side and said projecting file and cooperating with the latter for guiding the sharpener along the edge of the blade.

FRANK D. WULFF.
